TRIGGER MECHANISM FOR BOLT ACTION FIREARMS

Walter F. Roper, Longmeadow, and Frederick J. Wright, Springfield, Mass., assignors to Savage Arms Corporation, Utica, N. Y., a corporation of Delaware

Application February 20, 1953, Serial No. 338,048

1 Claim. (Cl. 42—69)

This invention relates to improvements in bolt action firearms and has particular reference to the trigger assembly mechanism for such arms.

An object of the invention is to provide a simplified structural assembly for the parts of the trigger mechanism and to provide a two piece trigger action with an improved safety construction.

The above and other objects and advantages of the invention will be best appreciated from the following detailed description of the mechanism as shown by the accompanying drawings, in which,

Fig. 1 is a side elevation of a bolt action repeating shotgun of the type embodying the present invention;

Fig. 2 is a longitudinal section showing the receiver and trigger parts in cocked position with the safety on;

Fig. 3 is a view similar to Fig. 2 with the safety off and the various parts in uncocked position;

Fig. 4 is a side elevation in reduced scale of the receiver and trigger housing; and

Fig. 5 is a section on line 5—5 of Fig. 4.

Referring more particularly to the drawings Fig. 1 shows a bolt action repeating shotgun with barrel 1 and receiver 2 having a bolt 3 and handle 4 slidable therein. The barrel and receiver are mounted on a stock 5 by a fore end assembling screw at 6. At 7 a magazine clip chamber is located with a magazine latch 8 at the rear thereof.

Shown in greater detail by Figs. 2 and 3 the bolt is provided with a firing pin 9 reciprocably mounted in the forward head portion 10 thereof. A bolt cap 11 having a longitudinal slot at 12 in the lower forward portion thereof receives in the slot the shouldered head 13 of the firing pin and embraces the reduced inner neck 14 of the bolt head with a retaining pin at 15 joining the cap and head. A cam collar 16 with a conventional camming surface at 17 is rotatably mounted on the neck 14 between the head 10 and cap 11. The receiver 2 is provided with a longitudinal slot 18 at the top thereof for receiving the stem of the handle 4 in cocking the gun in the usual manner.

Encased in the cap 11 is a hammer or striker pin 19 with spring 20 holding its enlarged head 21 against the head of the firing pin. Cap 11 at the top thereof is formed with a projecting shotgun bolt sight 22 for sighting along the top of the barrel in firing the gun.

The lower shouldered portion 13 of the firing pin head is formed with a cam receiving surface 23 in the front thereof and at the rear thereof is provided with a depending lug 24 having a rearwardly inclined sear engaging abutment on its forward face. The portion 13 of the firing pin is slidable forwardly in the slot 12 and in a longitudinal slot at 25 registered therewith in the lower section of the neck 14 of the bolt head to rest against the forward cam surface of the collar 16. The relative positions shown by Figs. 2 and 3 illustrate the travel of the firing pin.

The receiver is also slotted as at 26 for forward move-

ment of the lug 24 and to admit the top of a sear 27 for engagement with the lug.

As shown by Figs. 4 and 5 a trigger housing of narrow width is fixed to the under surface of receiver 2. The housing is preferably formed by folding a single piece of metal to provide closely spaced side walls 28 and a bottom wall 29 integral therewith. The free edges at the top of the walls may be integrally joined as by welding the same to the underside of the receiver. The rear edges of the side walls (Fig. 5) are outwardly turned to form flanges 30 against which in flat planar relation a plate 31 is fixed as by spot welding to provide a pad lying against the flat rear surfaces of a recess 32 of the stock. Between the forward edges of the walls 28 is a T-shaped piece, the leg 33 of which is fixed as by spot welding between the walls for spacing the same, and the cross head 34 of which forms a guide plate for the slotted edge of a magazine clip 35. Adjacent the leg 33 (see Fig. 2) on a pivot 36 fixed between the walls a U-shaped latch 37 is mounted, the foot of the latch having a toe 38 at the front thereof to engage the magazine and an extension 39 at the rear providing a finger plate by which the latch can be swung against a spring 40 to release the magazine.

Between the walls 28, the trigger action (Figs. 2 and 3) is mounted. The sear 27 and a trigger 41 are pivoted on pins 42 and 43 respectively. The pins are one above the other and may be substantially in vertically spaced relation rearwardly of the slot 26 and the depending lug 24 of the firing pin. The sear as shown is pivoted adjacent the extreme rearward portion thereof and forwardly weighted while the trigger is pivoted in its forward section and rearwardly weighted.

The sear is provided with an upwardly extending lug engaging face adapted for slidable engagement against the forward face of the lug as shown by Fig. 2. The sear is roughly in the form of an L-shaped piece with the pivot 42 at the top of the longer member thereof, the shorter member being forwardly and upwardly angled and adapted to lie with the lug engaging face at the upper rear corner thereof nested in the upper cocked position of Fig. 2 against lug 24. At the underside of the longer arm and intermediate the pivot and lug engaging face a sear notch is provided in a depending bulged projection having an inverted V-spaced recess at 45. The sear notch is adapted to receive an upwardly directed nose 46 of the trigger 41. The tip of nose 46 and the apex of the notch are substantially equidistant from the pivot pins 42 and 43 when in the cocked position of the parts as in Fig. 2 so that rocking movement of a trigger pull will cause the forward edge of the nose to slip off the fore side of the notch and permit the lug 24 to force the sear to the released position of Fig. 3. It will also be seen that the forward side of the sear notch 45 is in acute angular relation to a radial line drawn from the axis of pivot 42 to the apex of said notch. Thus in the engaged position of Fig. 2 the trigger nose 46 will hold the sear against movement until the trigger is rocked in a clockwise direction.

The forward portions of the sear and trigger are both yieldably urged to rotate in an upward direction by a spring 50. The spring is seated against the trigger in a notch 51, located above trigger pivot 43 and rearwardly of the pivots 42 and 43. Against the sear the spring is seated in a notch 52, below sear pivot 42 and forwardly thereof between the pivot 42 and sear notch 45. On the sear the force is exerted against the lower side thereof in an upward direction toward its forward end and on the trigger against an upwardly directed shouldered portion at 53 behind the pivot 43. Thus, in firing the gun the trigger is rocked against the spring 50 and the resistance of the sear which is urged in a counterclockwise

direction by the action of lug 24 under pressure from the spring 20. When the nose 46 slips past the sear notch 45 the sear slips under lug 24 and the firing pin is released. The sear 27 is also urged upwardly by the spring 50. The force of spring 50 is, however, overcome by the action of the far heavier spring 20 actuating the firing pin member 9 through the striker 19. The nose of the trigger, as seen by Fig. 3, thus rides to the forward side of the notched projection to remain in this position until the cam collar is rotated to cock the firing pin rearwardly against the spring 20. Spring 50 will then move the sear upwardly into engagement with lug 24 and at the same time the nose 46 will slip into the notch 45 as the spring 50 rocks the trigger by rearward pressure against the shoulder 53.

In dismantling the bolt from the receiver by withdrawing the handle 4 back along the slot at 18 it will be seen that the upwardly pressed sear can be swung downwardly to a greater degree by giving the trigger an additional pull to contact at the top thereof the rear edge of the sear and hold the front portion thereof out of the path of the bolt as it passes the slot at 26. As is common in bolt action repeating shotguns of this type the under-surface of the bolt head is generally slotted longitudinally as at 10' and provides a stop surface at the front of the slot to engage the sear to limit rearward travel of the bolt in ejecting a shell and re-loading the gun from the magazine clip.

The safety device as shown by Figs. 2 and 3 includes a pivoted locking member 55 held on pin 56 between the housing walls above the rear side of the shoulder 53. Shoulder 53 is notched with a horizontally disposed shelf at 57 to receive the lower edge of member 55 when the latter is swung forwardly into the position of Fig. 2. Above the pin 56 the safety 55 is formed with upstanding ears 55' between which is received the inturned foot 58 of a safety slide piece 59 (Fig. 4), the foot projecting through a slot 60 in the adjacent wall of the trigger housing. The slide 59 is recessed in the side of the receiver immediately above the trigger housing and is mounted for reciprocation in the recess by open ended slots in the front and rear edges as at 61 riding on spaced detent spring mounting screws at 62.

Between the slots in the central portion of the slide two closely spaced vertical detent slots at 63 provide a recess for the centrally scored crease 64 of a leaf spring detent 65 mounted by the screws 62. A finger piece to actuate the slide is provided above the recess at 66. As will be seen the detent 64 is lodged in the forward slot 63 of Fig. 4 and thus the slide is in the rearward position thereof in safety on position with the foot 58 holding the piece 55 nested against the shelf 57 of the trigger. In the forward position of the slide the foot 58 rocks the lower end of the lock member 55 rearwardly and out of the path of the trigger shoulder to permit pulling the trigger to the position shown by Fig. 3.

In the safety on position it will further be appreciated that any jarring of the butt stock of the gun will urge the slide 59 rearwardly and the lock member 55 forwardly towards the safety on position. With the two piece construction of the trigger action as shown the trigger is effectively locked against any inadvertent jarring of the sear to accidentally release the firing pin.

From the above description it will be seen that a simplified and fool-proof mechanism is provided in a gun of the type shown. The trigger housing walls may be made from a stamped piece of metal to eliminate any machining and bent to the form as shown for welding to the receiver. The pivot pins held by the walls are secured in place by spring clips embracing the heads thereof as indicated at 70 (Fig. 4) for ease in mounting and removing the same. As further indicated by Fig. 4 visibility openings 71 and 72 are provided in one of the walls 28 so as to enable inspection of the action of the trigger and sear at the sear notch and in the area of spring 50. Thus the accuracy and operation of these vital parts of the mechanism can be observed without dismantling the assembly.

What is claimed is:

In a firearm, a receiver and housed in the receiver a spring actuated reciprocable firing pin having a depending lug with a rearwardly inclined sear engaging abutment on the forward face of the lug for engagement in cocked rearward position of the pin, trigger mechanism including a pair of wide, flat, spaced sear and trigger housing plates dependent from the receiver and extending along the receiver beneath the firing pin forwardly of the sear engaging abutment of the firing pin lug, a sear pivoted between said housing plates adjacent its rear end rearwardly of said firing pin and said sear engaging abutment and having at its forward end an upwardly extending lug engaging face adapted for slidable engagement against the forward face of said lug in the upper pivotal position of the sear, said sear having a sear notch in its under-surface intermediate said pivot and said abutment engaging face, a trigger pivoted between said housing plates vertically below said sear pivot and provided at the forward tip thereof with a nose portion engageable in said sear notch in the upper abutment engaging position of said sear, said trigger holding said nose frictionally lodged in said notch and the sear in said sear abutment engaging position and being movable to release said sear for sliding pivotal movement thereof from the path of said firing pin lug, said trigger and sear having edge portions with aligned spring seating notches between the pivots of the trigger and sear diagonally disposed with relation to a vertical line between the pivots, a spring compressed between the trigger and sear and having one end seated in the spring seating notch in the trigger to engage the trigger above and rearwardly of its pivot and another end seated in the spring seating notch in the sear to engage the sear intermediate its pivot and the sear notch, said housing plates forming side walls for the spring seating notches of the trigger and sear and encasing the spring in said notches between the housing plates.
